US0D1079870S

(12) **United States Design Patent** (10) Patent No.: **US D1,079,870 S**
(45) Date of Patent: ** Jun. 17, 2025

(54) **GOLF CLUB HEAD**

(71) Applicant: **PARSONS XTREME GOLF, LLC**,
Scottsdale, AZ (US)

(72) Inventors: **Matthew G. Anciaux**, Phoenix, AZ
(US); **Caleb S. Kroloff**, Phoenix, AZ
(US)

(73) Assignee: **PARSONS XTREME GOLF, LLC**,
Scottsdale, AZ (US)

(**) Term: **15 Years**

(21) Appl. No.: **29/905,746**

(22) Filed: **Oct. 25, 2023**

(51) LOC (15) Cl. **21-02**

(52) U.S. Cl.

USPC **D21/759**

(58) **Field of Classification Search**

(57)

CLAIM

The ornamental design for a golf club head, as shown and described.

DESCRIPTION

FIG. 1 is a top perspective view of a golf club head;
FIG. 2 is a rear perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines shown on the drawings form no part of the claimed design.

1 Claim, 4 Drawing Sheets
